UNITED STATES PATENT OFFICE.

NORMAN W. STORER, OF PITTSBURGH, PENNSYLVANIA, ASSIGNOR TO WESTINGHOUSE ELECTRIC & MANUFACTURING COMPANY, A CORPORATION OF PENNSYLVANIA.

MEANS FOR SUPPRESSING FLASH-OVERS IN ROTARY-CONVERTER SYSTEMS.

1,392,087.

Specification of Letters Patent. Patented Sept. 27, 1921.

Application filed July 25, 1918. Serial No. 246,758.

To all whom it may concern:

Be it known that I, NORMAN W. STORER, a citizen of the United States, and a resident of Pittsburgh, in the county of Allegheny, and State of Pennsylvania, have invented a new and useful Improvement in Means for Suppressing Flash-Overs in Rotary-Converter Systems, of which the following is a specification.

10 My invention relates to means for minimizing or preventing commutator flash-overs in rotary-converter systems, and it has for its object to provide a system of the character designated wherewith the desired 15 result may be secured in a simple, effective and inexpensive manner.

Figure 1 of the accompanying drawing is a diagrammatic view of two rotary converters, together with associated load and 20 supply circuits and auxiliary apparatus embodying two forms of my invention; and Figs. 2, 3 and 4 are similar views of other forms of my invention.

In my copending application, Serial No. 25 203,527, filed Nov. 23, 1917, I describe and claim means whereby a plurality of points in the armature winding of a direct-current generator are interconnected in the event of 30 abnormal current flow therefrom, whereby the magnetically stored energy of the armature winding is immediately dissipated and the field magnetism is neutralized.

By this means, the energy, which would otherwise be available for initiating and 35 maintaining flash-overs, is so promptly and effectively dissipated as to largely minimize or entirely obviate this disastrous action.

In my copending application, Serial No. 222,083, filed March 13, 1918, I describe and 40 claim the application of similar means to a rotary converter for a similar purpose. In order to obviate short-circuiting of the transformer secondary winding, I disclose the application of suitable auxiliary slip rings 45 to the rotary-converter armature, these slip-rings preferably being tapped substantially midway between the main alternating-current-supply slip-rings. By placing the flash-over suppressing short-circuit upon the auxiliary slip-rings, the machine energy is 50 quickly dissipated without short-circuiting the transformer secondaries.

In further investigating this general sub-

ject-matter, I have found that a portion of the flash-over difficulty arises from the energy magnetically stored within the supply transformer, as well as from that stored in the converter itself and, furthermore, upon the occurrence of a flash-over, energy is supplied thereto from the system. It becomes 60 desirable, therefore, that effective means be provided for the reduction or prevention of energy flow from all three of these sources to the flash-over arc.

I find that, if a portion or all of the leads 65 between a supply transformer and a rotary converter be promptly interconnected upon the occurrence of flash-over conditions within in the converter or if, under like conditions, an impedance device be inserted in said 70 leads, flash-overs may be effectively suppressed without impressing undue current stress or strain upon the primary side of the supply transformers, particularly if, as is usually the case, the transformers embody 75 from 15 to 20% reactance. As an extreme case of the insertion of impedance in the supply leads, they may be opened, this being equivalent to the insertion of infinite resistance.

After a short interval of time, the flash-over preventing means may be returned to the normal position, thus again putting the converter into service or, if preferred, the adjustment may be such that the alternating-current circuit-breaker opens, thus freeing 85 the entire system.

Not only is the present system susceptible of application to a single rotary-converter, as above described, but, furthermore, I may 90 supply the same to a plurality of rotary converters, deriving their alternating current from distinct secondary windings of a supply transformer, as is occasionally the case. Under these conditions, the close inductive relation existing between the different secondary transformer windings effectively transfers a large portion of the stored energy of the transformer to the energy circuit first to come into action.

Referring to Fig. 1 of the accompanying drawings for a more detailed understanding of my invention, a rotary converter is shown at 2 embodying an armature 3 and an exciting field-magnet system 4 and, similarly, a rotary converter is shown at 5 em-

bodying an armature 6 and a field-exciting system 7.

Energy for the operation of the converters 3 and 6 is derived through a transformer 8 embodying primary windings 9 and two distinct sets of secondary windings 10 and 11.

The secondary winding 10 is connected to energize the armature winding of the converter 2 through suitable slip-rings, as is the usual practice, although, for simplicity and clearness, I have indicated the supply leads 12, 13 and 14 as permanently attached to points in the windings. In like manner, supply leads 15, 16 and 17 connect the secondary winding 11 to the winding of the armature 6.

Direct current is derived from the winding of the armature 3 through a commutator of any desired construction and supplied to direct-current buses 18 and 19, although, in order to still further enhance the simplicity and clearness of the drawing, I have shown the direct-current brushes 20-20 as bearing directly upon the armature winding, in accordance with familiar drafting practice. In like manner, direct-current brushes 21-21 derive current from the winding 6 for supply to the same direct-current buses 18 and 19.

30 A direct-current circuit-breaker 22 is shown connected between the winding of the armature 3 and the bus 19 and, in like manner, a direct-current circuit-breaker 23 is inserted between the winding of the armature 6 and the same bus. An alternating-current circuit-breaker 24 may be inserted in the supply leads of the transformer primary winding 9, if desired.

40 A relay switching device 25 is arranged to have its operating winding energized by the load current of the converter 2 and, when energized to or above a predetermined degree, serves to interconnect the supply leads 12, 13 and 14, as through conductors 26, 27 and 28. In like manner, a relay switching device 29 serves to interconnect the supply leads 15, 16 and 17, as through conductors 30, 31 and 32, upon the occurrence of flash-over producing means within 50 the converter. The operating winding of the relay 29 is in circuit with the field winding of the exciting pole 7 of the converter 5, thus rendering the relay 29 sensitive to flash-over-producing conditions in the manner fully discussed in a copending application of C. M. Moss, Serial No. 242,623, filed June 20, 1918, and assigned to the Westinghouse Electric & Manufacturing Company. A marked advantage of this 60 method of operating the relay over the method shown in connection with the converter 2 is that the device is operative upon internal short circuits in the machine 6, the effect of a short-circuit being to change the 65 armature field, radically decreasing the ex-

pecting field and, therefore, causing a pronounced increase in the field current in accordance with Lenz's law.

The switching devices 25 and 29 are preferably quick-acting in their response to a current increase, preferably being so designed as to establish a good conducting path between the associated supply leads well within the time required for a portion of the armature winding to pass from one brush to the other or, in other words, to pass from a condition of maximum positive potential to a condition of negative potential.

Having thus described the arrangement 80 of a system embodying my invention, the operation is as follows: It being assumed that the current taken from the buses 18 and 19 exceeds a predetermined amount so that, for example, the switching device 25 85 closes. The supply leads 12, 13 and 14, interlinking the converter 2 with the supply transformer secondary windings 10, are promptly interconnected and there is an instantaneous and pronounced flow of circulating currents from the secondary windings 10 to the point of interconnection and from the winding of the armature 3 to the same point. The flow of current from the supply system is promptly shunted or bypassed around the converter 3 so that it is ineffective in supporting the flash-over arc. Furthermore, the working flux of the transformer 8 is promptly and radically reduced in value, thus radically reducing the magnetically stored energy of the transformer 100 itself contemporaneously with the decrease of magnetically stored energy within the converter, substantially all of this magnetically stored energy being dissipated in the 105 heating effect of circulating currents flowing through the temporary short circuit thus established.

During the same period of time, the magnetic interconnections within the transformer 8 are such that the energy inter-linked with the secondary winding 11 is also dissipated, thus reducing the tendency to flash-over in the machine 5 as well as in the 110 machine 2.

In due time, the circuit breaker 22 associated with the machine 2 opens the direct-current circuit, thus completely removing the machine 2 and causing the switching device 25 to open and, if desired, said breaker 115 120 may be arranged to directly open the interconnection, as through suitable auxiliary contact members. The breaker 22 may, furthermore, simultaneously open the field circuit of the machine 2, all as described in detail in the aforementioned applications.

The operation of the protective apparatus associated with the converter 5 will be obvious from the foregoing description. A sudden increment of load current within 130

the armature winding of the armature 6, from any cause whatsoever, either an internal short-circuit or an external short-circuit, demagnetizes the field pole 7 and causes 5 an inductive rise of current in the field circuit. The switch 29 at once closes, interconnecting the supply leads and protecting the machine 5, at the same time protecting the machine 2 by reason of the inductive 10 relationship between the secondary windings 10 and 11.

If desired, the adjustment may be such that the alternating-current circuit-breaker 24 opens prior to the direct-current circuit-breakers, thus relieving the entire bank of 15 rotary converters, upon the operation of the flash-over-suppressing circuit.

Upon casual consideration, it would seem that disastrous effects would follow the direct interconnection of the secondary windings 20 of a supply transformer but if, as is frequently the case, the inherent reactance of the transformers amounts to 20% or 30%, as is employed, for example, in the control 25 of the output voltage of the converter by the alternating-current reactance method, the total current flowing on the primary side of the transformer is maintained within reasonable limits until such time as the 30 transformer is freed, either by the operation of the direct-current or alternating-current circuit-breakers.

Referring to Fig. 2, I show a converter at 33 comprising an armature 34 and an exciting 35 field pole 35, the latter being provided with an exciting winding 36. Energy is supplied to the slip rings of the converter 33 from a transformer 8, and a direct-current load circuit is connected to the brushes 40 in the usual manner. Impedance devices 37, 38 and 39 are inserted in the supply leads from the transformer 8 to the converter and these impedance devices are normally short-circuited by the contact members of a 45 relay device 40. The operating winding of the device 40 is in circuit with the field winding 36, whereby the impedance devices 37, 38 and 39 are first inserted in circuit, upon the flow of such abnormal current in 50 the field circuit as will actuate the device 40 and the armature winding of the rotary converter is then short-circuited through the back contacts of the device 40 for the dissipation of the stored energy.

55 The impedance devices 37, 38 and 39 are indicated as ohmic resistors but they may be either condensive or inductive in nature if desired. These impedance devices may well be those normally employed in reducing the 60 voltage supplied to the converter during starting and, to this end, means may be provided such as an operating handle 41, whereby the impedance devices may be rendered effective at the will of the operator.

65 In the form of my invention shown in Fig.

3, the general arrangement of circuits is as before except that a relay device 42, when opened, serves to first disconnect the transformer from the converter, and to then short-circuit the armature winding of the 70 rotary converter, the device 42 being, in effect, an alternating-current circuit-breaker of the self-closing type provided with back contact members. This breaker may be rendered quick opening and slow closing, as 75 by a biased dash-pot 43 and if the time required for closing is quite appreciable such, for example, as a second or more, the converter 83 will, in most cases, clear itself of flash-over conditions and be prepared for 80 the resumption of service upon the closing of the circuit breaker 42.

In the system of Fig. 4, a relay device 45 is arranged to short-circuit an auxiliary secondary winding 46 on the transformer 8 85 upon the occurrence of overload conditions, thus largely eliminating the flow of load current through the transformer and inductively absorbing the stored energy from the working secondary winding 9. The operating winding of the relay device 45 may be energized by any of the above-described methods or, as shown, it may be energized from the terminals of an auxiliary winding 47 mounted on the field pole 35. This latter 90 connection is of advantage where the normal changes in the field excitation of the winding 36 are quite pronounced, although 95 gradual. Such changes in the energization of the field winding 36 produce little or no 100 effect upon the winding 47, although the abrupt change in the exciting field flux caused by flash-over conditions induces a pronounced electromotive force in the winding 47, irrespective of the current then flowing in the winding 36.

From a consideration of the above-described circuits and of the circuits shown in the copending applications to which reference is made, it will be apparent that there 110 is a large number of different combinations and arrangements that may be effected for bringing about the general results herein produced, and these possibilities may be analyzed as follows. In the first place, there 115 are three points from which the operating effect may be produced, namely, from the alternating-current mains, from the direct-current mains and from the exciting field circuit. The operating effect may be derived 120 either directly or inductively, as by the use of current transformers associated with the alternating-current supply mains or by an auxiliary winding placed upon the supply transformer or upon the exciting field pole. 125

Having derived the desired operating effect, it may be applied in short-circuiting the armature winding itself, either at the tap points, as by short-circuiting the slip rings, or by interconnecting points other 130

than the tap points. The operating effect may further be employed to insert either finite or infinite impedance in the supply leads between the transformer and the converter and it may be employed to short-circuit an auxiliary winding placed directly upon the armature, as disclosed in a copending application of B. G. Lamme, Serial No. 240,422, filed June 17, 1918, and assigned 10 to the Westinghouse Electric & Manufacturing Company or by short-circuiting an auxiliary winding upon the supply transformer.

In construing the breadth of the present invention, it is desired that all of the above 15 possible combinations be borne in mind, whether completely described and illustrated or not, and that the claims be construed accordingly, it obviously being needless to encumber the present description 20 with a detailed description of all the possible combinations.

If desired, as in an automatic substation, means may be provided for again automatically placing the system in operation but 25 such means constitute no part of the present invention and I deem it unnecessary, therefore, to encumber the disclosure and discussion with a detailed description thereof.

I claim as my invention:

30 1. The combination with a rotary converter, of a source of alternating current and a load circuit connected thereto, respectively, and means for simultaneously imposing a relatively high-impedance short-circuit 35 upon said source and a relatively low-impedance short-circuit upon said converter upon the occurrence of flash-over producing conditions within said converter.

2. The combination with a rotary converter, of a supply transformer therefor, a load circuit connected thereto, and means 40 for interconnecting at least two supply leads between said transformer and said converter upon the occurrence of abnormal current flow in said load-circuit.

3. The combination with a rotary converter, of a supply transformer therefor having relatively large reactance, a load circuit connected thereto, and means for interconnecting at least two supply leads between 45 said transformer and said converter upon the occurrence of abnormal current flow in said load-circuit.

4. The combination with a rotary converter, of a supply transformer therefor, a load-circuit connected thereto, and a relay device arranged to interconnect at least two supply leads between said transformer and said converter upon the occurrence of abnormal current flow in said load circuit, said device being designed to complete said interconnection in less time than is required for a

given point in the armature winding of said rotary converter to pass from a condition of maximum positive potential to a condition 65 of maximum negative potential.

5. The combination with a rotary converter, of a supply transformer therefor, a load-circuit connected thereto, a relay device arranged to interconnect at least two supply 70 leads between said transformer and said converter upon the occurrence of abnormal current flow in said load circuit, said device being designed to complete said interconnection in less time than is required for a given point in the armature winding of said rotary converter to pass from a condition of maximum positive potential to a condition 75 of maximum negative potential, and a relatively slow-acting circuit-breaker arranged 80 to open said load circuit upon the occurrence of said abnormal current flow.

6. The combination with a dynamo-electric machine of the commutator type, of 85 means responsive to flash-producing conditions for automatically interconnecting a plurality of points in the armature winding in such manner as to form a symmetrical close-circuited polyphase winding.

7. The combination with a dynamo-electric machine of the commutator type, of 90 means responsive to flash-producing conditions for automatically producing a poly-axially close-circuited winding for screening the field flux from the armature conductors undergoing commutation.

8. The combination with a supply transformer, of a plurality of rotary converters connected to derive energy therethrough, and a device dynamically associated with said 100 transformer and adapted to dissipate the stored energy thereof and of said machines upon the flow of abnormal current in one of said machines.

9. The combination with a supply transformer, of a plurality of rotary converters connected to derive energy therethrough, and a device dynamically associated with 105 said transformer and adapted to dissipate the stored energy thereof and of said machines upon the flow of abnormal current 110 in any one of said machines.

10. The combination with a rotary converter, of a supply transformer connected to transmit energy thereto, a load circuit 115 connected to be energized from said rotary converter, and means for simultaneously dissipating the stored energy of both pieces of apparatus upon the flow of abnormal current in said load circuit.

In testimony whereof I have hereunto 120 subscribed my name this 22nd day of July, 1918.

NORMAN W. STORER.
